 Certain-Teed Products Corporation, New York,
 N. Y., a corporation of Maryland

Application November 29, 1938, Serial No. 242,883

11 Claims. (Cl. 108—7)

This invention relates to covering materials and more especially to covering elements intended to be laid in courses in overlapping relation. The invention particularly relates to covering elements or shingle strips of the type which have tabs depending from the body portion and separated by spaces of similar dimensions to those of the tabs.

Covering elements and shingle strips of the type above referred to have been utilized in many forms with rectangular, hexagonal, arcuate and other outlines of the tabs and recesses. One advantage of such types of elements or shingle strips is that a surface or roof may be covered with less material than is requisite for the type of shingle strip in which, for the purpose of more closely simulating the roof constructions which utilize individual elements such as wood shingles, the shingle strip is formed with tabs separated by cut-outs of such narrow width as to simulate only the space between individual shingles or like covering units. While with the wide-spaced-tab shingle strips a full double coverage of the surface or the roof deck is usually not obtained, as is the case with the so-called "cut-out" shingle just referred to, nevertheless for many purposes adequate protection is secured with less expense than is possible with the cut-out shingle.

While wide-spaced-tab shingle strips have been used in various forms over a long period, it is common experience that the roofs or surfaces covered therewith do not present an attractive appearance nor do they secure in the covered surface either a desirable texture or a simulation of individual covering units, such as wood shingles, laid in the usual closely spaced relation in courses with the usual variations in width and thickness as well as in the spaces between the units contributing to the characteristic texture of such roofs or coverings. In order to secure the necessary protection such wide-spaced-tab shingle strips must in general be laid with the butt edge of the tab adjacent the inner line or edge of the recess between tabs of the subjacent shingle strip. This arrangement not only usually produces a pattern of regular form in the roof, in many cases of geometric form as in the hexagon shingle strip, but any attempt to depart from this arrangement involves modification of the usual forms to make certain that the tabs shall cover the joint formed at the edges between two shingle strips in the subjacent course and that at least single coverage is maintained. If this joint is not covered by a tab leakage through the roof will occur, there being, with the strip of

usual dimensions, no third course completely underlying which will carry such leakage outward from under the strips forming the joint. Thus, departure from the regular arrangements of such wide-spaced shingle strips and the resultant regular or geometric patterns which are produced in the roof is difficult or impossible.

The present invention maintains the features of the usual wide-spaced-tab shingle strips which accomplish the necessary protection by providing a body portion in the strip from which the spaced tabs depend. This body portion is of sufficient width transversely of the coursewise dimension of the strip to underlie the inner edge of the recess between the tabs of a superposed strip when the lower edges of the tabs of said superposed strip are placed adjacent, preferably substantially in register with, the inner edges of the recesses of the subjacent strip. Preferably, also, the tabs of the shingle strip of the invention, as with those of the prior art, are positioned upon the strip to be symmetrical with the coursewise dimension of the body of the strip so that, as in the prior art strips, the joint which is formed between two shingle strips in the same course will be covered by the tab of a superposed strip.

Moreover, the invention utilizes the device of certain prior art shingles which provides upon the tab area a color or appearance which is in contrast with the color or appearance of the body of the strip. Thus, when a shingle strip in a superposed course is placed with its lower tab edges adjacent the inner edges of the recesses between tabs of a subjacent course, the area of the subjacent strip appearing between the tabs of such a superposed strip contrasts in appearance with that of the tabs in said superposed strip. There is thus provided in the shingle strip of the invention the basis for variation of the appearance of the different areas in the roof and avoidance of a dead appearance such as results from the assembly in a covering or a roof of shingle strips, such as hexagonal shingle strips, having all one color. Such prior art shingles, however, lack features which are provided by the present invention to produce the simulation of individual shingles laid in courses. Even where irregular variegation of the color of the shingle strip has been adopted, as heretofore proposed, such variegation has not accomplished or contributed to the formation of areas which may be identified as shingle simulating areas which, as will be shown, is a feature of the invention.

The prior art shingles of the wide-spaced-tab type are additionally lacking in having no provis-

ion for carrying out the simulation of the butt in the two contrasting areas, namely, the tab area and the surface of the subjacent shingle exposed between the tabs of the overlying shingle. In other words, in the prior art shingles the area lying between the tabs has been without demarcation which would make this area simulate a shingle or covering unit. The covering element or shingle of the invention provides for definite demarcation of the tab area from the body portion of the covering element or shingle strip. This it accomplishes by the formation thereon of a stripe of substantial width extending in the coursewise direction generally along the boundary of the body portion of the element from which the tab of the element depends. For example, in a strip embodying the invention which has tabs of generally rectangular outline separated by a recess of generally rectangular outline, the inner edge of the recess and the extensions thereof across the tab areas substantially constitute the boundary of the body of the element which has been referred to. In accordance with the invention the stripe conveniently may be placed upon such a shingle strip so as to extend the full length of the shingle strip and may, for example, have one edge thereof coincident with the inner edge of the recess, the width of the stripe lying fully upon the body portion of the shingle strip. If desired, however, this stripe may be applied with a portion of its width upon the area of the tab itself and a portion upon the body of the strip. In some cases the stripe may be applied with its full width upon the tab portion of the strip. By these variations in the position of the stripe there may be accomplished the effective simulation of covering elements or shingles having different lengths of exposure transversely of their coursewise dimension.

A particular feature of the invention is that provided by the formation of the stripe which has just been described with a width in the direction transversely of the coursewise dimension of the shingle strip such that when the shingle is upon a roof, usually a sloping surface, the fore-shortened width of this stripe as viewed from the ground appears to be similar to and preferably at least equal to the thickness of the tabs of the shingle or of an individual covering unit positioned in the roof with its butt edge at the position of said stripe. The stripe being positioned on the shingle strip as above described, so as to extend generally along the boundary at which the tabs join the body of the strip, it will be understood, and more clearly seen in connection with the description of the drawings to follow, that the lower edge of the tab of a superposed shingle will be generally in line with the stripe as it is exposed crossing the tab of the subjacent shingle strip and between the tabs of the overlying shingle. If the strips are assembled in the roof with the lower edge of the tabs adjacent and preferably substantially in register with the inner edges of the recess of the subjacent shingle, then, even though the stripe be formed with a part or all of its width upon the body portion of the strip, the portion of the stripe which extends between tabs on the same shingle strip becomes covered by a tab of the superposed shingle. It will be apparent, therefore, that in such an assembly of the elements or shingle strips of the invention there is secured the simulation of individual shingle elements arranged in courses. The simulation of certain shingles in one course is accomplished by the tabs and the simulation of the

adjacent and intermediate shingles in the same course is accomplished by the exposed area of the body of the subjacent shingle, the butt edge simulation for this area being accomplished by the stripe. Moreover, the demarcation, as has been described above, of this simulated shingle from the shingle of the course beneath is also accomplished by the stripe. 5

It is a further feature of the invention that this stripe may be of sufficient width so that it not only offsets the foreshortening effect which has been referred to above to obtain a simulation of the thickness of a butt of a shingle, but also provides as well for the simulation of the shadow cast by such a butt of a shingle. This width further may be made sufficient to produce the effect of double thickness of the shingle strip material which exists in the covering assembly or roof construction which has been referred to, wherein the tabs are positioned substantially in register with the inner edges of the recess in the subjacent shingle. Thus, while in the prior art for brick simulations in material to be used on a vertical wall a narrow line has been produced upon a shingle having a pair of spaced tabs depending from a body portion thereof, this line extending below the lower edge of the body portion and across the tab areas for simulation of the horizontal mortar line between bricks, there has not been proposed in the prior art the formation of a stripe of sufficient width to give the effect of the butt thickness or the butt thickness plus the shadow cast thereby. Preferably the width of this stripe is many times the thickness of the material or roofing element upon which it is formed and of such width that if viewed directly rather than at an angle as from ground to roof it would simulate neither the butt edge nor a masonry joint. 25

The invention will be more particularly understood from the following description to be taken in connection with the drawing in which

Fig. 1 shows a shingle strip embodying the invention.

Fig. 2 shows a modified form of the shingle strip of the invention.

Fig. 3 is an assembly of the elements of Fig. 1.

Fig. 4 is an assembly of the elements of Fig. 2.

Fig. 5 shows the method of cutting elements of the invention from sheet material. 50

In Fig. 1 the shingle strip 1 is provided with a body portion 2 of generally rectangular form. From the edge 3, which substantially constitutes the lower boundary of the body portion 2 of the element 1, depend tabs 5 of generally rectangular outline, these tabs being spaced apart by the recess 7 which is of generally like form and dimension to that of the tabs 5. Preferably the tabs 5 and the recess 7 are of such similar form and dimension that in cutting a plurality of the shingle strips from a sheet the tab of one strip may be cut from the recess formed between tabs on the other strip in a manner illustrated in Fig. 5, thus saving waste of material in producing such shingle strips. The tabs 5 thus have a depth 60 from the edge 8 to line or edge 3 of the body portion substantially equal to the depth of the recess 7 and it will be seen in this embodiment that the inner edge 9 of the tab areas is substantially coincident with the extension of the edge 3 across 70 the tab areas. Moreover, it will be seen that the inner edge of the recess 11 is substantially in line with the lines 9 forming the inner boundary of the tabs. 55

In the manner referred to above, upon the

body portion 2 of the shingle strips 1 is formed by suitable means a stripe 13 having its lower edge substantially coincident with the boundary line 3 of the body portion and with said lines 9 and 11 respectively of the tab areas and of the inner edge of the recess 7. The upper line 14 of the stripe 13 is positioned a substantial distance above the line 3 to form a stripe of considerable width, this stripe being preferably of darker appearance than the area of the tabs 5 or that of the body portion 2 of the shingle strip, this contrasting stripe providing the simulation of the butt of a shingle and its shadow as described above.

15 In a practical embodiment of the invention in a shingle strip, upon a base material, such as the usual saturated felt commonly used in roofing, a surfacing material may be bound by a coating of asphalt or other mastic. This surfacing material upon the tabs 5 may be of granular mineral material such as slate. Similarly, granular mineral material may be bound upon the body portion 2 of an element having such a base by the coating which also has been applied to this area of the shingle strip. This surfacing upon the body 2 may be of the same color or, if desired, may be of contrasting appearance to that on the tab areas 5. For reasons which will appear from the description of Fig. 3, the area 20 2 of the shingle strip of Fig. 1 may be provided with a series of lines 16 which conveniently may be made as depressions in the coating and extending in the direction transversely of the coursewise direction of the strip in generally parallel relation across this portion. These lines may be straight or may be wavy or irregular to produce different textures or appearance. An important function of these lines, however, is to carry the eye in the direction transverse to the course so as to accentuate this transverse dimension of the area of this body portion of the strip which, as it becomes exposed between tabs of a superposed strip, is less than the transverse-to-the-course dimension of the tab.

25 40 45 In the modification of the invention illustrated in Fig. 2, the tabs 5 are of contrasting color to the body portion 2 and are separated therefrom by a stripe 13 positioned generally along the lower boundary of the body portion similarly to the element of Fig. 1. It will be understood, however, in this modification that the lower edge 15 of the stripe in the portion thereof which extends across the tabs 5 is not coincident with the boundary line 3 of the body portion but is positioned below said boundary portion and, therefore, a portion of the width of the stripe 13 is upon the tab area 5. If the width of the stripe 13 between the lines 15 and 14 thereof is substantially the same as that illustrated in Fig. 1, that portion of the stripe which extends along the inner line 11 between the tabs is narrower than the portion extending across the tabs. Inasmuch, however, as the lower edges 8 of the tabs in the assembly, as will be understood from Fig. 4, are positioned substantially coincident with the inner edges 11 of the recesses, that is the lower boundary 3 of the body of the strip, this narrower portion 17 of the stripe becomes covered by the tab of a superposed shingle strip and the portion 18 of the stripe between the recesses, that is, extending across the tabs, is exposed in its full width so that it effectively demarks the tab area from the body portion of the strip as does the stripe 13 of Fig. 1. When it is viewed from the ground it becomes foreshortened and is

effective to simulate the butt edge and, if desired, the shadow cast thereby as well. There is thus simulated in the assembly a shingle element formed by the area of the body portion 2 lying between the tabs 5 of an overlying shingle element and between the stripe 13 of the subjacent element and the inner edge 11 of the recess on said overlying element in the same manner as in Fig. 3.

It will be further seen that along the lower edge 8 of the tabs 5 of the shingle strip of Fig. 2 there is provided a narrow stripe which, like the stripe 13, is of darker appearance than the tab area. It will be understood that this stripe 20 may be secured by the manner of cutting the shingle strips from a sheet illustrated in Fig. 5, since the edge 8 of the tab of one shingle strip will be cut along the edge 11 of the recess of the companion strip. Since the stripe is so positioned that the lower edge 15 of the stripe 13 is below the line 3 of the body portion of the strip the inner edge 21 of the stripe 20 upon the tab must become positioned upon the tab area of the interfitting strip and the stripe 20, therefore, becomes formed upon the tabs of the strips cut one from the other. Thus is secured upon the tab edge a shadow simulating stripe and one which accentuates the shadow cast by the tabs upon the surface of a subjacent shingle strip. The position of the stripe 13 on the shingle strip as- tride or in displaced relation to the line 3 of the body may be adjusted, and its own width may be varied so that it is capable of simulating the thickness of a shingle element or of the edges of the superposed thicknesses of the elements, or these thicknesses plus the shadow cast thereby, together with the accentuated shadow provided by the shadow stripe 20.

Describing Fig. 3 more particularly, it illustrates an assembly of the elements of Fig. 1 in a roof construction. It will be seen from Fig. 3 that the lower edge 8 of the tabs of the elements of the type of Fig. 1 are positioned substantially in register with the inner edge 11 of the recesses 7 between the tabs 5 of the subjacent elements. 45 The body portion 2, therefore, becomes exposed between the tabs 5, this body portion in the particular embodiment illustrated in Figs. 1 and 3 being of the same color but being of contrasting appearance to that of the tab by virtue of the 50 lines 16 across this body portion. Contrast in the areas thus may be secured both in the coursewise direction and in the direction up and down the roof. While the shingle strips are laid in courses of these strips in the usual manner, each 55 strip of the invention contributes to the simulation of two of the simulated courses of shingle elements by virtue of the stripe 13 cooperating with the tabs and the edges of tabs and recesses. Alternate shingle simulating areas in a course 60 of such simulated elements are provided by the tab areas 5 and intermediate simulated shingle elements are provided by the body portions 2 exposed between the tabs. In the direction proceeding up or down the slope of the roof also, alternate simulated shingle elements in different courses are provided by the tab areas 5 and the intermediate simulated shingle elements are provided by the body portions 2 exposed between the tab areas and demarcated at their lower boundary 65 70 by the stripe 13.

This feature has not been secured in the prior art shingle strips of the wide-spaced-tab type. In the prior art strips, such as the hexagon shingle strip in common use, the hexagons con- 75

stitute merely the element of the design in the roof and the eye follows from the one hexagon to the other. In prior art constructions utilizing wide-spaced-tab strips having rectangular tabs the eye also carries from one rectangle to the other. These areas are in staggered arrangement in both the coursewise direction and in the slope of the roof. There is not secured in either of these constructions a representation of a coursewise arrangement of shingle simulating elements. Moreover, in the prior art constructions which have provided differences in color between the body portion and the tab area there is not provided, as by the stripe 13, the definite demarcation of the area 2 from the tab areas 5 with the resulting simulation of thickness of a shingle element for the area 2 cooperating with the actual thickness of the tab 5, as it is seen at its edge, and particularly in the construction of the type to which the invention relates where the tab edge 8 becomes superposed above the recessed edge 11, presenting the appearance of two thicknesses of the roofing material.

In Fig. 4 the features described in connection with Fig. 3 are also maintained. Because, however, of the position of the stripe 13 on the shingle strip of Fig. 2, as incorporated in the roof construction of Fig. 4, a number of advantageous features are secured in such a roof construction. As has been described above, the stripe 20 along the edge 8 of the tabs 5 accentuates the thickened appearance of the tab in its position above the exposed edge 11 of the recesses. By making the stripe 13 of proper width when the roof construction of Fig. 4 is viewed from the ground, at the usual distance from the building, the area 2 exposed between the tabs has along its lower boundary and demarking it from the tab area 5 in the subjacent course of simulated shingle elements means which is effective to produce the appearance of the thickness of the shingle element simulated by the area 2. If desired, this stripe may be made wide enough to simulate this edge and, as well, the shadow cast by this area upon the tab area 5 therebelow. It will be noted from Fig. 2 and particularly Fig. 4 that the area of the stripe 13 as it is exposed between two tab areas in the same simulated courses of the elements is of markedly different width than the stripe 20 upon the butt edge of the tabs 5. Moreover, whereas in Fig. 3, utilizing the elements of Fig. 1, the area 2 exposed between the tabs at either side thereof is of substantially less width transversely of the courses than is the tab area 5, it will be noted that in the assembly of Fig. 4, the area 2 which becomes exposed between tabs is more nearly of the same transverse-to-the-course width. This results from the position of the stripe 13 upon the element of Fig. 2 with respect to the edge 3 as has been described above. Nevertheless, it also will be seen from Fig. 4 that the upper line 14 of the stripe 13 is not in line with the upper line 21 of the stripe 20. There is produced, therefore, some irregularity in the appearance of the edge of the simulated course of shingle units, which coursewise edge comprises the portions of the element of the invention provided by the actual edges of the tabs 5 plus the actual edge 11 of the subjacent element and the portion afforded by the stripe 13 as it is exposed between the tabs of a superjacent element. It will be understood, however, that the position of the stripe 13 may be selected so that this irregularity may be obtained or a substantially straight coursewise edge may be simulated for the simu-

lated course of roofing elements or shingles. Moreover, the position of this stripe 13 upon the shingle strip relative to the edge 3 thereof as well as its width transversely of the coursewise dimension may be varied to secure both the appearance of differences in thickness and of different lengths of exposure of the simulated tabs of shingle elements and the irregular edge appearance of the course.

In Fig. 5 is illustrated a method of cutting from a sheet of material shingle elements of the type illustrated in Figs. 2 and 4. This method makes it possible to produce without waste of the material shingle elements having a stripe 20 on the tab edge thereof and having the stripe 13 along the boundary 3 of the body thereof. In Fig. 5 upon a sheet 30 and spaced equidistant from the side edges 31 and 32 of said sheet are formed, by any convenient method suitable for obtaining the stripe 13 upon the shingle element 20 as has been described, a pair of stripes 33. Symmetrical with the center line 36 of the sheet 30 is cut, by any usual means such as a cylinder cutter past which this sheet is fed, a cut 37 of staggered outline having portions 38 extending lengthwise of the sheet and within the area of the stripes 33. The portions 38 are connected by the cuts 39 transversely of the length of the sheet to form square tabs with recesses therebetween on the strips of material which thereby will be cut from the sheet at either side of the staggered cut 37. In the particular method illustrated in Fig. 5 the cuts 38 are made nearer the edges 34 of the stripes 33 which are positioned nearer the center line of the sheet. If, for example, the cuts 38 within the stripes 33 are made $\frac{1}{4}$ " from the edges 34 and if, for example, the width of the stripes 33 is 1", then cuts 38 will be made at a distance of $\frac{3}{4}$ " from the outer edges 35 of the stripes 33. It will now be clear how the stripe 20 on the tab 5 of the shingle element of Fig. 2 may be produced by the method illustrated in Fig. 5. It also will be clear that by varying the position of the cuts 38 with respect to the longitudinal edges 34 and 35 of the stripe 33 and also taking into account the width of the stripe 33 the variations which have been described above for the stripes 20 and 13 and the effects produced by these variations may be secured.

The amount of foreshortening of the dimension of any unit placed in a roof which extends up and down the slope of the roof is considerable in the ordinary slopes of roofs, so much so that the design effect produced by cutting the edges of prior art shingles in different outlines may be substantially lost. If, for example, a dimension of 1" along the slope of a roof, sloping at 45°, is viewed directly horizontal, this dimension of 1" will appear to be about $\frac{1}{6}$ ". In a roof on a house of moderate size a point at the center of the slope of the roof may be, with usual ceiling heights and the height of first floor above the ground, about 28 to 30 feet above the ground. If such a point is seen from the ground at a distance of say 65 to 80 feet from the house, as for example when viewed from the opposite side of the street, this dimension of 1" of slope of the roof becomes very much more foreshortened. This foreshortening becomes very much increased if the roof is viewed from a distance of about 40 feet, for example from the near side of the street.

In the first instance, and assuming that the horizontal distance from the point to be viewed from the position of the observer is 80', the 1" dimension along the slope of a roof would be

- reduced to somewhat less than $\frac{1}{2}$ ". When the point selected is viewed from the near side of the street, this dimension of 1" becomes reduced to less than $\frac{1}{4}$ ". It thus will be apparent that the 5 width of a stripe of 1" upon the strip of the invention may be foreshortened to appear to be from one-quarter to one-half of the actual width of the stripe. In other words, a stripe width of 1" would simulate the thickness of two superposed layers of shingle material each $\frac{1}{8}$ " to $\frac{1}{4}$ " thick depending on the point from which they are seen. When consideration is given to the 10 existence of actual shadow from the butt edge of the shingle element or from a tab or from the superposed edges of shingle elements and having 15 in mind the desirability of also impressing the eye with this shadow to simulate the normal effect in a roof of shingle elements in courses, still further accentuation of the width of the stripe will be required for shingle elements of the thickness just mentioned. Thicknesses of less than the range of $\frac{1}{8}$ " to $\frac{1}{4}$ " are more usual and may be secured together with their shadow simulation by means of a stripe of the degree of 1" in width. 20
- 25 In view of the variations in roof slopes and variations in thickness of shingle elements of various materials this width within the scope of the invention may be varied from about $\frac{3}{4}$ " to $1\frac{1}{2}$ ". It is not intended that the invention shall be limited to such widths but that a stripe shall be provided upon the element which is markedly greater than the thickness of the shingle elements to be simulated and may be greater than this thickness plus the shadow cast thereby. 30
- 35 The invention is not strictly limited to the configuration of the tabs illustrated in the drawing nor to a shingle having a stripe of uniform width and rectilinear extent. Variations of these features as well as of the relative areas of the tabs and the exposed portions of the body and also of the relative positions of the shingle strips in one course relative to those in another may be practiced within the scope of the invention while maintaining the feature of a demarcation stripe of exaggerated width transversely of the coursewise direction for simulation of the butt edge of a shingle and of its shadow.
- Having thus described my invention I now claim:
- 50 1. A roofing element for laying in overlapping courses, said element having a tab depending from a coursewise boundary of the body of the element, said tab having a coursewise dimension such that when the body portions of two elements 55 are abutted in the same course a space is left between the tabs of said adjacent elements having a coursewise dimension of the degree of said tab to leave exposed between said tabs a portion of the body of the element in the subjacent course, said element having thereon a stripe of darker appearance than the tab and body areas of the 60 said element, said stripe being positioned on the element to extend in the coursewise direction generally along said boundary of the body of the element to mark the tab area from the body of the element, said stripe having a width transverse to the coursewise length thereof in consideration of the usual slopes of the roof deck such that the foreshortened width of the stripe as viewed from the ground is at least as great as the thickness of the tab, said tab along the butt edge thereof having a stripe of a darker appearance than the 65 surface of the tab to accentuate the shadow cast by the tab, the width of said butt edge shadow stripe upon the tab being substantially equal to the width of that portion of said stripe along said boundary of the body of the element which is upon the tab area.
- 55 2. A roofing element for laying in overlapping courses, said element having a plurality of tabs positioned thereon along a coursewise boundary of the body of the element, said tabs being separated in the coursewise direction by spaces having a width of similar degree to that of the tabs, 70 said element having thereon a stripe of darker appearance than the tab and body areas of the element, said stripe being positioned on the element to extend in the coursewise direction generally along said boundary of the body of the element to mark the tab areas from said body of the element, said stripe having a width transverse to the coursewise length thereof in consideration of the usual slopes of the roof deck such that the foreshortened width as viewed from the ground is at least as great as the thickness of the tab. 75
3. A roofing element for laying in overlapping courses, said element having a plurality of tabs positioned thereon along a coursewise boundary of the body of the element, said tabs being separated in the coursewise direction by spaces having a width of similar degree to that of the tabs, 80 said element having thereon a stripe of darker appearance than the tab and body areas of the element, said stripe being positioned on the element to extend in the coursewise direction generally along said boundary of the body of the element to mark the tab areas from said body of the element, said stripe having a width transverse to the coursewise length thereof in consideration of the usual slopes of the roof deck such that the foreshortened width as viewed from the ground is at least as great as the thickness of the tab. 85
4. A roofing element for laying in overlapping courses, said element having a plurality of tabs positioned thereon along a coursewise boundary of the body of the element, said tabs being separated in the coursewise direction by spaces having a width of similar degree to that of the tabs, 90 said element having thereon a stripe of darker appearance than the tab and body areas of the element, said stripe being positioned on the element to extend in the coursewise direction generally along said boundary of the body of the element to mark the tab areas from said body of the element, said stripe having a width transverse to the coursewise length thereof in consideration of the usual slopes of the roof deck such that the foreshortened width as viewed from the ground is at least as great as the thickness of the tab, said tab along the butt edge thereof having a stripe of a darker appearance than the surface of the tab to accentuate the shadow cast by the tab. 95
5. A shingle strip having a pair of generally rectangular tabs spaced apart by a generally rectangular recess a distance in the coursewise direction of the degree of the width of the tabs, said shingle strip being provided with a stripe extending in the coursewise direction substantially along the extension of the inner edge of said recess across the tab area, said stripe having a width such that as foreshortened when the shingle strip is upon the roof and is viewed from the ground it approximates the thickness of the butt edge of the tab. 100
6. A shingle strip having a pair of generally rectangular tabs spaced apart by a generally rectangular recess a distance in the coursewise direction of the degree of the width of the tabs, said shingle strip being provided with a stripe extending in the coursewise direction substantially along the extension of the inner edge of said recess across the tab area, said stripe having a width such that as foreshortened when the shingle strip is upon the roof and is viewed from the ground it approximates the thickness of the butt edge of the tab. 105

- rectangular tabs spaced apart by a generally rectangular recess a distance in the coursewise direction of the degree of the width of the tabs, said shingle strip being provided with a stripe extending in the coursewise direction substantially along the extension of the inner edge of said recess across the tab area, said stripe having a width such that as foreshortened when the shingle strip is upon the roof and is viewed from the ground it approximates the thickness of the butt edge of the tab plus the width of the shadow cast by the butt edge of the tab upon the shingle beneath in an assembly of shingles in overlapping courses.
7. A roof construction comprising a plurality of shingle strips each having a plurality of tabs of substantial width in the coursewise direction spaced apart by recesses having a width in the coursewise direction of similar degree to that of the tabs, said shingle strips being assembled in the courses with the lower butt edge of each tab adjacent the inner coursewise edge of the recesses of a shingle strip in the course beneath and with a portion of the body of a subjacent strip from which the tabs depend exposed between the tabs of the superposed shingle strip, said shingle strips having thereon stripes extending in the coursewise direction in the region where the tabs join said body portions of the shingle strips so as to be exposed between said tabs of a superposed shingle to demark shingle simulating areas in two adjacent courses of shingles, said stripes being of a width substantially greater than the thickness of the material of the tabs, whereby as foreshortened when viewed from the ground said stripe appears as the butt edge of a tab.
8. A roof construction comprising a plurality of shingle strips each having a plurality of tabs of substantial width in the coursewise direction spaced apart by recesses having a width in the coursewise direction of similar degree to that of the tabs, said shingle strips being assembled in the courses with the lower butt edge of each tab adjacent the inner coursewise edge of the recesses of a shingle strip in the course beneath and with a portion of the body of a subjacent strip from which the tabs depend exposed between the tabs of the superposed shingle strip, said shingle strips having thereon stripes extending in the coursewise direction in the regions where the tabs join said body portions of the shingle strips so as to be exposed between said tabs of the superposed shingles to demark shingle simulating area in two adjacent courses of shingles, said stripes having a width transverse to the coursewise length thereof great enough in consideration of the usual slopes of the roof deck substantially to offset the foreshortening effect when viewed from the ground and to approximate the thickness of the tab plus the width of the shadow cast by the tab upon the exposed portion of a subjacent shingle.
9. A shingle strip having a pair of generally

rectangular tabs spaced apart by a generally rectangular recess a distance in the coursewise direction of the degree of the width of the tabs, said shingle strip being provided with a stripe extending in the coursewise direction substantially along the extension of the inner edge of said recess across the tab area, said stripe having a width of between $\frac{3}{4}$ " and $1\frac{1}{2}$ ".

10. A roofing element for laying in overlapping courses, said element having a tab with substantially parallel side edges depending from a coursewise boundary of the body thereof, said tab having a coursewise dimension such that when the body portions of two elements are abutted in the same course a space is left between the tabs of said adjacent elements having a coursewise dimension of the degree of said tab to leave exposed between said tabs a portion of the body of the element in the subjacent course, said element having thereon a stripe of darker appearance than the tab and body areas, said stripe being positioned on the element to extend in the coursewise direction generally along said boundary of the body of the element to demark the tab area from the body of the element, said stripe having a width transverse to the coursewise length thereof in consideration of the usual slopes of the roof deck such that the foreshortened width of the stripe as viewed from the ground is at least as great as the thickness of the tab, said body portion of said strip being provided with a series of spaced lines extending generally parallel to the side edges of the tabs which carry the eye in the direction transverse to the course as to accentuate the transverse dimension of the area of the body portion exposed between tabs of a superposed course of elements.

11. A roofing element for laying in overlapping courses comprising a felted fibrous base saturated and coated with asphalt and surfaced with granular material, said element having a tab with substantially parallel side edges depending from a coursewise boundary of the body thereof, said tab having a coursewise dimension such that when the body portions of two elements are abutted in the same course a space is left between the tabs of said adjacent elements having a coursewise dimension of the degree of said tab to leave exposed between said tabs a portion of the body of the element in the subjacent course, said element having thereon a stripe of darker appearance than the tab and body areas, said stripe being positioned on the element to extend in the coursewise direction generally along said boundary of the body of the element to demark the tab area from the body of the element, said stripe having a width transverse to the coursewise length thereof in consideration of the usual slopes of the roof deck such that the foreshortened width of the stripe as viewed from the ground is at least as great as the thickness of the tab.
